UNITED STATES PATENT OFFICE.

FRED J. HOYT, OF CHICAGO, ILLINOIS.

FASTENER FOR MEETING-RAILS OF SASHES.

SPECIFICATION forming part of Letters Patent No. 395,274, dated December 25, 1888.

Application filed September 25, 1888. Serial No. 286,839. (No model.)

To all whom it may concern:

Be it known that I, FRED J. HOYT, a citizen of the United States, residing at Chicago, in the county of Cook and State of Illinois, have 5 invented certain new and useful Improvements in Window-Locks; and I do hereby declare the following to be a full, clear, and exact description of the invention, such as will enable others skilled in the art to 10 to which it appertains to make and use the same.

My invention relates to window-locks, and its object is to improve such locks in the matter of simplicity and efficiency.

15 It consists of the parts hereinafter described and claimed.

It is illustrated in the accompanying drawings, in which—

Figure 1 is a front view in elevation of two 20 sashes locked by my lock; Fig. 2, a side elevation, in section, of sash and lock; and Figs. 3, 4, 5, and 6, details, the latter being a plan.

Referring to the drawings, A is an upper sash and B a lower one.

25 C is a metal socket, sunk into the inner ledge, d, of the upper sash and provided with a top, D, having shoulders e, which rest on the ledge of the upper sash and to which they are secured by bolts. The top D is formed 30 with a cradle, f, having sides g extending over and at right angles with the socket C, and is provided with a central hole, h, leading into the socket.

H is a pin fitted into the sides g of the top

D, extending across the cradle and directly 35 over the center of the hole h and the socket C.

I is a pin provided with a slot, j, and hung by said slot on the pin H.

When the window is unlocked, the pin I rests in a vertical position in socket C, as 40 shown in Fig. 2. When the sashes are closed and it is desired to lock them, the pin is withdrawn from the socket and turned down in the cradle f, with its head over the ledge of the inner sash and with its opposite end extended 45 through the cradle f and over the ledges of the upper sash. In this position the locking-pin is held from turning by its bearing on the pin H, and neither sash can be moved up or down until the locking-pin is pulled out from the 50 cradle f, so that it can be turned up and returned to the socket. To give a smooth bearing on the ledge of the lower sash, one shoulder, m, of the head of the pin is cut away or a square flat-headed or other shaped pin 55 might be used.

What I claim is—

A window-lock composed of a metal socket, a cradle-top over such socket having a hole leading into the socket, a pin, H, across said 60 cradle, and a slotted pin, I, hung on the pin H, substantially as described.

In testimony whereof I affix my signature in presence of two witnesses.

FRED J. HOYT.
